J. A. EBERLE.
CHILD'S SWING.
APPLICATION FILED FEB. 18, 1920.

1,403,675.

Patented Jan. 17, 1922.

UNITED STATES PATENT OFFICE.

JOHN A. EBERLE, OF ST. LOUIS, MISSOURI.

CHILD'S SWING.

1,403,675.

Specification of Letters Patent. Patented Jan. 17, 1922.

Application filed February 18, 1920. Serial No. 359,676.

To all whom it may concern:

Be it known that I, JOHN A. EBERLE, a citizen of the United States of America, and a resident of the city of St. Louis, and 5 State of Missouri, have invented certain new and useful Improvements in Children's Swings, of which the following is a full, clear, and exact description, reference being had to the accompanying drawings, forming 10 a part of this specification.

My invention relates to a child's swing intended more particularly for the use of infants, the invention having for its object the production of an inexpensive swing 15 which may be readily suspended at any desired location, and which when not in use may be folded compactly so as to occupy a very small space. One of the objects of the present invention is to provide a swing 20 comprising a pocket seat in which the child may be placed, the supporting frame members of said pocket seat being formed of a single endless wire, and the back and sides of said frame members against which the 25 child rests when the swing is in use being shaped to conform to the contour of the child's body. Heretofore it has been the practice in manufacturing swings of the class herein disclosed to connect the ends of 30 the wire frame members in such a manner as to cause a protuberance at point of connection which would cause discomfort to the occupant of the swing and would also cause the fabric forming the seat to wear 35 through at that particular point. By the use of a single endless wire I provide a perfectly smooth frame member which eliminates the foregoing objections.

Another object of my invention is to provide 40 a swing of the class described, the seat of which may be readily adjusted to any desired distance from the floor.

Fig. I is a front elevation of my swing.

Fig. II is a side elevation.

45 Fig. III is a sectional plan showing one of my endless wire seat frame members in full lines.

Fig. IV is a section on line IV—IV of Fig. III.

50 Fig. V is a fragmentary detail illustrating the adjusting device for regulating the distance of the seat of the swing from the floor.

In the drawings A designates the pocket 55 of the seat of my swing preferably made up of canvas or fabric of any other suitable

description, and comprising a bottom web B, a straight front portion C and curved side and back portions D. The front corners of the bottom web B have formed herein a pair of openings B' through which the legs of a child occupying the seat may extend.

1 designates an upper frame member comprising a U-shaped portion 2 to which the sides and back of the seat are secured, and a straight front portion 3 connecting the ends of the U-shaped portion, the front of the said seat pocket being secured to this straight portion. The walls of the pocket 70 A are secured to the frame member 1 preferably by folding the material at the upper margins of the said walls over the frame and stitching the fold.

A lower frame member 4, which is a 75 counterpart of the frame member 1 except that it is of smaller dimensions, is secured to the walls of the seat at the bottom thereof in the same manner as the frame 1, i. e., by folding the fabric over the frame and 80 stitching the fold. The function of the frame member 4 is to keep the lower portion of the seat in the proper shape and prevent undue distortion of the said seat when a child is placed therein.

85 It is apparent that if this lower frame member 4 was not used, the seat A would sag downwardly with the weight of a child, thereby drawing the fabric of which said seat is formed tightly about the body of the 90 child, resulting in a rather uncomfortable seat. Another disadvantage of pocket seat having no lower frame member is that the seat proper is distorted by the weight of a child in the said seat, and the leg holes 95 therein will likewise become misshapen and contracted so as to pinch the child's legs therein. By the use of a pair of upper and lower frame members secured to the fabric pocket as herein shown, I provide a seat 100 the shape of which is maintained when the said seat is occupied, and because the bottom web B upon which the child is seated is securely anchored to the rigid frame 4 at its outer margins, very little sag is possible, and the leg holes in the said web will not be distorted by the weight of the child.

105 5 designates suspension straps secured to the frame 1 and which lead upwardly to a spreader 6. The application of these straps 110 to the frame 1 is permitted by slightly exposing the said frame through the material

of the pocket A and the straps 5 are attached at points where the swing will be properly and substantially supported thereby.

5 Upper suspension straps 7 secured to the spreader 6 lead upwardly and pass through an eye formed in the hanger 8. An adjusting member 9 secured to the upper end of the suspension strap 7 and provided with 10 an aperture 10 through which the said suspension strap 7 passes, serves to regulate the distance of the pocket A from the floor. To adjust the pocket A upwardly or downwardly it is necessary to bring the adjusting member 9 to a position at right angles to the suspension straps 7, in this position the said adjusting member 9 may slide freely on the said suspension straps. When the adjusting member 9 has been placed at 15 the desired location, the weight of the swing and its occupant will cause the said adjusting member to be drawn to a position approximately as is shown in Fig. V of the drawing, in which position the suspension 20 straps 7 will be crimped by the gripping edges of the aperture 10 of the adjusting member 9, thereby preventing any movement of the said suspension straps relative 25 to the said adjusting member.

I claim:

30

1. A child's swing having a flexible seat pocket, frame members secured to the upper and lower portions of said seat pocket, each of said frame members comprising a single endless wire having a U-shaped side and 35 rear portion and a straight front portion connecting the ends of the U-shaped portion, and suspension means secured to the upper frame member.

2. A child's swing having a flexible seat 40 pocket, upper and lower frame members comprising single endless wires each having a U-shaped side and rear portion and a straight front portion connecting the ends of the U-shaped portion, the front, sides, 45 and back of the said seat pocket being secured at the upper margins thereof to said upper frame member, said seat pocket having a flat bottom web secured at its outer margins to said lower frame member, said 50 flat bottom web being provided with leg holes at the front corners of the lower frame member, and suspension means secured to one of said frame members.

In testimony that I claim the foregoing I 55 hereunto affix my signature.

JOHN A. EBERLE.
